FURNACE FOR STEAM BOILERS.

JOHN F. MYERS, OF KOKOMO, INDIANA.

Letters Patent No. 60,229, dated December 4, 1866.

SPECIFICATION.

TO ALL WHOM IT MAY CONCERN:

Be it known that I, JOHN F. MYERS, of Kokomo, in the county of Howard, and State of Indiana, have invented a new and useful improvement in Furnaces for Steam Boilers; and I do hereby declare that the following is a full, clear, and exact description of the same, reference being had to the annexed drawings, making a part of this specification, in which—

Figure 1 is a perspective view, part of the brick-work being represented as broken away to show the interior structure.

Figure 2 is an elevation showing the rear end.

The same letters are employed in both figures in the indication of identical parts.

The object of this invention is to so arrange a furnace for a steam boiler that the heat may be turned away from the boiler, and the boiler be exposed to the action of currents of cold air for the rapid reduction of pressure and the avoidance of explosions. This purpose I effect by the following arrangement of the furnace:

Immediately in rear of the grate-bars, at the front edge of the bridge wall, I place a hinged door, B, turned by a crank, B'. The door is formed to fit, and when raised to close, the throat of the furnace entirely; when down it lies upon the bridge wall, and does not impede the draught of the chimney. I also construct doors C in the side of the furnace wall, and likewise doors E in the end opposite the flue H. In order to permit the escape of the draught, I form pipes, G, leading from the fire-box into the breeching, or directly into the stack. This pipe may be opened and closed by a valve at I. When the door B is raised the valve I is opened, and the heat passes directly into the stack; at the same time, the doors in the wall being opened, the cold air is admitted to the outside of the boiler, and through the doors in the rear a strong blast will be carried by the draught of the stack through the internal flues of the boiler, thus very rapidly cooling the water contained in the boiler, and relieving the pressure thereon.

What I claim as my invention, and desire to secure by Letters Patent, is—

1. A furnace for a steam boiler when constructed with a door or valve, B, for closing the throat of the furnace, and with doors through the exterior walls of the furnace for the admission of cold air to the surface of the boiler and flues, substantially in the manner and for the purpose set forth.
2. In combination with a door, or valve B, as described, I claim the pipes G, and valves I, arranged to operate substantially as and for the purpose set forth.

JOHN F. MYERS.
